UNITED STATES PATENT OFFICE.

GEORGE CUTTER, OF BOSTON, MASSACHUSETTS.

COMBINATION-TOOL.

SPECIFICATION forming part of Letters Patent No. 322,914, dated July 28, 1885.

Application filed June 6, 1885. (No model.)

To all whom it may concern:

Be it known that I, GEORGE CUTTER, of Boston, (Somerville,) in the county of Middlesex, State of Massachusetts, have invented a certain 5 new and useful Improvement in Combination-Tools, of which the following is a description sufficiently full, clear, and exact to enable any person skilled in the art or science to which said invention appertains to make and 10 use the same, reference being had to the accompanying drawings, forming part of this specification, in which—

Figure 1 is a side elevation of my improved combination-tool represented as closed; Fig. 15 2, a vertical longitudinal section of the same, and Fig. 3 a side elevation showing it arranged as a pair of dividers or compasses.

My invention relates to that class of combination-tools which are designed, principally, 20 for domestic use; and it consists in a novel construction and arrangement of the parts, as hereinafter more fully set forth and claimed, the object being to produce a simple, durable, and effective implement, which embodies 25 in compact form all of the desirable features and characteristics of the various tools which enter into the combination.

The nature and operation of the improvement will be readily understood by all conversant with such matters from the following 30 explanation, its extreme simplicity rendering an elaborate description unnecessary.

In the drawings, A represents the handle; B, the bradawl, and C the screw-driver. 35 The body of the bradawl is flat, and provided with an elongated slot, D, and point E. The body of the screw-driver is flat and provided with a wide point, m, and narrow point x, to adapt it to fit screws of different 40 sizes, the narrow point being slightly thinner than the wide point.

A set-screw, H, provided with a washer, b, passes through the slot D, and is fitted to work in a threaded hole in the center of the 45 body of the screw-driver, thereby pivoting said driver and enabling it to be readily reversed or turned end for end.

A socket, t, is formed in the lower end of the handle A, said socket being adapted to

receive either end of the screw-driver C. 50 The lower end of the body of the bradawl B is tapered, and provided with a cutting-edge, f, at either side to form the countersink z. The bradawl is also provided with angular or cutting edges, being square in 55 cross-section where it joins the countersink, and tapered to its point. It may, however, be made round, if preferred. The shank k of the bradawl, where it enters the handle A, stands at one side of the longitudinal axial 60 line of said handle, said line, when projected, passing between the bradawl and screw-driver.

To prepare the tool for use either as a bradawl or countersink, the screw H is loosened 65 and the screw-driver C withdrawn from the socket t and secured in a horizontal position by said screw.

When the tool is used as a screw-driver, the wide point m or narrow point x, as the case 70 may be, is inserted in the socket t, and the driver firmly secured to the body of the bradawl by the screw H.

The object in setting the bradawl at one 75 side of the axial line of the handle is to equalize the eccentricity of the awl and screw-driver. I do not, however, confine myself to this arrangement, as either the screw-driver or bradawl may be set on the axial line of the handle, if preferred.

The bradawl may be made round or of any other suitable form desired.

It will be obvious that when the bradawl is used to make a screw-hole, the hole may be readily countersunk to receive the head of 85 the screw at the same time.

Having thus explained my invention, what I claim is—

1. In a tool, substantially such as described, the combination of the following instrument- 90 alities, to wit: a handle, a bradawl, a countersink, and a screw-driver, the countersink and bradawl being integral or formed in one piece, the screw-driver being provided with two ends adapted to engage a screw, and adjustably connected with the body of the bradawl, and the handle provided with an open 95 socket adapted to receive either end of said

driver and house the same when the driver is arranged for use.

2. The improved combination-tool herein described, the same consisting of the handle 5 A, provided with the open socket t, the screw-driver C, provided with the points *m* *x* and screw H, and the bradawl B, provided with

the slot D, countersink z, and point E, constructed, combined, and arranged to operate substantially as set forth.

GEORGE CUTTER.
